UNITED STATES PATENT OFFICE

WALTER HALL HANSFORD, OF EARLWOOD, NEAR SYDNEY, NEW SOUTH WALES,
AUSTRALIA

MOTOR SUSPENSION SPRING REBOUND DAMPER

Application filed December 22, 1930, Serial No. 504,137, and in Australia December 28, 1929.

This invention relates to double acting spring rebound dampers (so-called "shock absorbers") of the oscillating vane hydraulic type containing an adjustment device for regulating the degree of damping imposed on the suspension spring movements.

The invention consists in a novel construction of the vane and spindle assembly and an improved regulating valve of the axial pin type for controlling the by-pass circulation of oil between the chambers.

The structural features in which the invention consists are shown in the accompanying perspective sections:—

15 Fig. 1 being a broken sectional view of the complete apparatus; and

Fig. 2 a broken sectional view of the spindle, vane, and valve.

The casing or cylinder consists of a base 20 plate 10 and a cylindrical cap 11 spigot jointed to the base plate 10 as shown at 12 and fixed by two through pins 13 which serve also as fixing bolts for which purpose they are extended through the chassis frame 14, 25 behind which nuts are screwed onto them. The inner end of the vane spindle 15 is centered in a hole 16 bored in the interior face of the base plate 10 in alignment with a stuffing box 17 formed in the ribbed up cap portion 18 of the cylinder body 11. The outer end of the spindle 15 is squared as shown at 19 and upon this square end the eye of a lever arm which is connected by a link to the spring crown or the axle of the vehicle is fixed by a 35 key which engages the notch keyway 20. The chamber is divided into two sections by neatly fitted segmental blocks 21. The holding bolts 13 pass through these segmental blocks 21 and retain them in fitted position.

40 The interior faces 22 of the segmental blocks 21 are very neatly fitted to the spindle 15 to prevent oil leakage past the joint but the other three faces are close fits for the top, bottom, and wall of the chamber.

45 The spindle 15 is transversely slotted and a slide vane 23 is fitted through the slot. This vane is a close sliding fit for the top, bottom, and side walls of the chamber, and two cross slots 24 are cut through one edge of it, the 50 ends of these slots emerging as shown at 25

clear of the face of the spindle 15. The regulator spindle 26 is a close fit in an axial hole 27 bored through the vane spindle, the bore being extended into the lateral part of the vane 23 at the crossings of the grooveways 24. 55 At this place flats 28 are formed on both sides of the regulator spindle 26. The outer end of the spindle 26 extends through a throat nut 29 screwed into the outer end 19 of the vane spindle; this nut bears against a collar 30 which is integral with the regulating spindle 27, and a backing washer 31 is set behind the collar 30. When the collar nut 29 is screwed hard home the washer 31 is compressed and leakage of oil along the regulating spindle is effectively checked; this spindle is adjusted by means of a spanner applied to its protruding flats 32, the adjusting being effected while the collar nut 29 is slackened off. 60 The area of clearance for the passage of oil through the grooveways 24 is determined by the position of the flats 28. If the spindle 26 be so adjusted that a very small clearance only is allowed, then the cushioning effect of oil contained in the chambers (this oil being 65 introduced through the filler hole 33) is a maximum, and the dampering effect will be a minimum. When the spindle is adjusted to allow more clearance, the cushioning effect is diminished. The apparatus may therefore 70 be adjusted quite readily by slightly rotating the control spindle 26 to set the flat faces 28 for the required clearance for passage of oil from one pair of segmental chambers to the other pair of segmental chambers. The 75 flats 28 are parallel and consequently adjustment of the spindle's position results in providing an equal clearance for passage of oil through both grooveways 24. The respective ends of the vane work in the respective 80 segmental chambers and when the spindle 15 is oscillated by the oscillatory movement of the axle of a car transmitted through the lever arm which is fitted on the spindle arm 19, the oil is placed under corresponding 85 compression and forced from one pair of chambers to the other pair of chambers through the grooveway passages 24, clearance provided by the adjustment of the control spindle 26 being regulated so that oil may 90 95 100

pass through these grooveways at a rate corresponding with the dampering or cushioning effect required for easing of the oscillatory motions of the vehicle consequent upon 5 running over irregular road surfaces.

What I claim as my invention and desire to secure by Letters Patent is:—

1. In a suspension spring damper of the 10 rocking vane segmental chamber type, a chamber having a base plate and a cap and being divided by partition segments held by fixing bolts which clamp the chamber body to the base plate a vane spindle footed in the base plate, a control spindle fitted axially in 15 the vane spindle, crossed slot passageways in the vane connecting the four chambers, and flats formed on the control spindle where it meets the crossed slot passages, all constructed substantially as described with reference 20 to the accompanying drawings.

2. In a suspension spring damper, a casing 25 having an internal chamber, partitions arranged in said casing and subdividing said chamber, a spindle pivotally mounted in said casing and having a slot therethrough, and a flat vane fitted through said slot and having its ends snugly fitting the interior of the casing, said vane having crossed grooves formed 30 in one side thereof connecting the portions of said chamber lying at opposite sides of said vane.

3. In a suspension spring damper, a casing 35 having an internal chamber, partitions arranged in said casing and subdividing said chamber, a spindle pivotally mounted in said casing and having a slot therethrough, and a flat vane fitted through said slot and having its ends snugly fitting the interior of the casing, said vane having crossed grooves 40 formed in one side thereof connecting the portions of said chamber lying at opposite sides of said vane, said spindle having an axial bore communicating with said slot, and a control spindle mounted in said bore and controlling 45 passage through said grooves.

In testimony whereof I affix my signature.
WALTER HALL HANSFORD.
